UNITED STATES PATENT OFFICE.

WILLIAM B. HARTLEY, OF WATTS, CALIFORNIA.

HELICOPTER.

1,153,073.

Specification of Letters Patent. Patented Sept. 7, 1915.

Application filed July 24, 1914. Serial No. 852,944.

To all whom it may concern:

Be it known that I, WILLIAM B. HARTLEY, a subject of the King of Great Britain, residing at Watts, in the county of Los Angeles and State of California, have invented new and useful Improvements in Helicopters, of which the following is a specification.

This invention relates to means in helicopters or lifting, sustaining and driving propellers for flying machines, the particular object in view being to provide a propeller which will efficiently sustain the machine in a hovering attitude, and adapt the machine for direct vertical ascent and descent.

A further object of the invention is to provide a helicopter of increased lifting and sustaining efficiency and which is so constructed as to prevent radial air slippage, as well as to effect the compression and reaction of the air in such a way as to utilize the dynamical reaction of the air to the highest possible degree.

A still further object of the invention is to provide a propeller which is simple of construction and adapted to be driven at either high or low speed and without the necessity of employing abnormally high driving power.

The invention consists of the features of construction, combination and arrangement of parts herein fully described and claimed, reference being had to the accompanying drawings in which:—

Figure 1 is a view in elevation of a propeller embodying my invention. Fig. 2 is also a view in elevation of the propeller looking toward the propeller in a direction at right angles to the view shown in Fig. 1.

Fig. 3 is a top plan view of the propeller. Fig. 4 is a bottom plan view of the same. Fig. 5 is a vertical section through the propeller on the line 5—5 of Fig. 3. Fig. 6 is a vertical section through the propeller on the line 6—6 of Fig. 3.

The propeller comprises a shaft 1 which carries the propeller proper, said propeller consisting of a pair of diametrically disposed semi-circular blades 2 and 3 fixed in any suitable manner to the shaft to revolve therewith. Each of said blades is of spiral contour, and has a concaved reaction surface 3, a convex reaction surface 4, an elevated leading edge 5, and a depressed trail edge 6, the leading edge of each blade terminat-

ing above and in rear of the trailing edge of the other blade. Each blade is provided with a peripheral flange 7, preferably depending therefrom at right angles thereto, and of major depth at the leading edge of the blade, and thence gradually decreasing in depth to a point about one-third of the circumferential dimensions of the blade, from which point to the trailing edge of the blade the flange is of uniform depth. Disposed beneath the leading portion of each blade is a sector shaped vane 8, which is attached at its base or wider edge to the deepened forward portion of the flange 7 and at its inner reduced edge or apex to the shaft 1, said vane being thus disposed at an angle to the leading portion of the blade so as to form a flue or channel 9 which is widest at its open end and is thence gradually contracted both circumferentially and radially, the flue or channel being thus constricted at its discharge point which terminates about in line with the vertical plane of intersection of the elevated leading and depressed trail portions of the blade.

In practice, the shaft carrying the propeller is mounted in any suitable manner upon the flying machine and is driven from a power plant of a suitable type. When the shaft is revolved in a forward direction, as indicated by the arrow in Fig. 3, the air is gathered and compressed beneath the spiral blades and reacts dynamically upon the lower or reaction surfaces of the blades to give a lifting and supporting action. The blades traveling in operation screw-fashion upon a correspondingly shaped compressed body of air, as will be readily understood. It is evident that as the body of air is acted upon by the elevated leading portion of each blade it is compressed and exerts its lifting impulse, the downward trend of air on its rebound causes it to strike and slide along the depressed trail portion of the blade, by which a secondary lifting impulse is secured and the period of sustaining or lifting travel of the blade upon the body of compressed air prolonged, with a resultant greater efficiency of lifting action. It will also be evident that the acting force of each blade upon the compressed air is in two directions, first vertical to give a lifting impulse, and second at an angle to the vertical to give both a lifting impulse and a forward driving or propelling effect. By rotating the propeller at different speeds the ma-

chine may be caused to travel directly upward from the ground, to hover or remain stationary in the air, to travel horizontally while sustaining, and to descend at any desired speed in a direct path to the ground.

The purpose of the flange is to confine the body of air beneath the blade while it is being compressed by the blade and exerts its reactive impulse thereon, to prevent the body of compressed air from prematurely flying off at a tangent whereby the full lifting impulse of the air is utilized and the power of the propeller correspondingly increased. The function of the vane is not only to provide the gathering channel, whereby the air is retained while being compressed, but also to act as a supplementary lifting surface, and to form with the deepened portion of the flange 7 a channel which by reason of its circumferential and radial contraction effects a higher degree of compression of the air than would otherwise be possible and the release of the compressed air after its force is fully utilized at a tangent to that to which it would normally take, so that the air in expanding and tending to discharge tangentially outward by centrifugal force will have substantially double the ordinary lifting effect and power.

A propeller thus constructed is designed to utilize different forces of the air due to

compression and other causes in the most efficient manner to secure lifting and driving effects, by which a propeller of great power is produced, and one which will have a 35 powerful lifting, sustaining and driving action without the necessity of employing an abnormally powerful driving plant to operate it, since it prevents the waste of lifting, sustaining, driving powers usually lost by 40 slippage and at the same time attains greater efficiency in these operations as a result of its peculiar action upon the air.

I claim:

A propeller comprising a shaft, diametrically disposed spiral blades carried by the shaft, each of said blades having an elevated leading edge and a depressed trail edge, a flange depending from the peripheral edge of each blade and of major depth 50 along the leading portion thereof, and a vane extending beneath the leading portion of each blade and between the flange and shaft, said vane forming with the leading portion of the blade a circumferentially and radially 55 flaring gathering channel.

In testimony whereof I affix my signature in presence of two witnesses.

WILLIAM B. HARTLEY.
